UNITED STATES PATENT OFFICE

H MILLER ANDERSON, OF CHICAGO, ILLINOIS, ASSIGNOR, BY MESNE ASSIGNMENTS, TO THE LAKE ERIE CHEMICAL COMPANY, OF CLEVELAND, OHIO, A CORPORATION OF OHIO

VAULT RELEASE

Application filed November 7, 1928. Serial No. 317,810.

The object of the invention is to provide an improved release mechanism for auxiliary locks for safes, vaults, and the like, which will function quickly and with certainty upon punching, blowing or other dislocation of the usual combination box, and which will also function quickly and certainly upon severing or burning of the door itself.

Numerous other objects and advantages of the invention will be apparent as it is better understood from the following description, which, taken in connection with the accompanying drawings, discloses a preferred embodiment thereof.

Referring to the drawings:

Figure 1 is a rear elevation of a vault door, showing diagrammatically the auxiliary locking mechanism, the bolt-work, the combination box, the protective wiring, and a release mechanism connected in the wiring system;

Fig. 2 is a vertical sectional elevation, taken through a vault door in the locality of the combination box, showing the release mechanism operatively connected therewith;

Fig. 3 is a vertical sectional elevation of the release mechanism, taken on the line 3-3 of Fig. 2;

Fig. 4 is a vertical section of said mechanism, taken on the line 4-4 of Fig. 3;

Fig. 5 is a bottom view of the release mechanism, showing the hinge construction, and taken on the line 5-5 of Fig. 3, and

Fig. 6 is a perspective view of a pellet, constituting one of the operating parts of the wiring release mechanism.

In the illustrative structure, an ordinary vault door is shown diagrammatically at 11 in Fig. 1, and the improved release mechanism is applied to the inside of said vault door. The vault door 11 is provided with the usual combination lock contained within the box or casing 12 mounted on the inner face of the door and controlling the operation of the bolt-work 13, which is projected through the usual bolt rail to lock the door and retracted to release the door.

An auxiliary locking mechanism for the door is shown diagrammatically at 14 and is controlled primarily by the disabling of

wiring 15, maintained normally under tension and adapted on release of said tension to set the auxiliary locking mechanism into operation.

As shown in Fig. 1, the wiring 15 is strung up and down on the inner face of the door 11 and at the top and bottom is trained about pulleys 16. One end 17 of the tensioned wiring leads to and is connected with the auxiliary locking mechanism 14 and on release of the tension of the wiring, however accomplished, the auxiliary locking mechanism is set into immediate operation to lock the door independently. The other end 18 of the protective wiring 15 is connected to a spring 19, which in turn is secured at 20 to the door 11. This spring 19 maintains the wiring 15 under tension and through the wiring restrains the auxiliary locking mechanism from operation.

The illustrative release mechanism provides for insuring a rapid positive disconnection of the wiring, so as to release its tension immediately upon punching, blowing, or other dislocation of the combination box or burning of the door. The release mechanism 21 is preferably located in the vicinity of the combination box 12 and the wiring 15 is guided by top and bottom pulleys 22, so as to pass to one side of the combination box and into operative relationship with the release mechanism.

The illustrative release mechanism is shown more particularly in Figs. 2 to 6 of the drawings. Secured to the inner face of the door 11, by screws 23 or other suitable fastening devices, is a fixed plate 24 provided with a longitudinally disposed channel or recess 25 extending from end to end of the plate.

The wiring 15 passes through the channel 25 within which it is to be interrupted as a result of attack upon the vault door and consists of two wires connected at their ends within the channel 25 and leading respectively to the spring 19 and relocking device 14. The punching or blowing of the combination box or the burning of the door results in disconnection of the two wire members of the wiring and in operation of the relocking mechanism 14. The ends of the two wires are connected together within the releasing device as will

now be described. Each wire end is provided with a loop 26-27 and these loops are passed about a disc or pellet 28 located in the channel or recess 25. The pellet has a thickness substantially equal to the depth of the recess and a plate 29 is employed to close the top of the recess and hold the pellet in engagement with and connecting the two loops 26-27.

As shown in Figs. 3 and 5, the fixed plate 24 is provided at its bottom and on each side of the channel 25 with a pair of spaced lugs 30. The pairs of lugs 30 respectively support pins 31 constituting pivots by which the movable plate 29 is hinged at its bottom to the fixed plate 24. As shown particularly in Figs. 4 and 5, the movable plate 29 is provided at its bottom with inwardly projecting ears 32 located on opposite sides of the channel 25 and having holes which receive the inner ends of the hinge pins 31.

Coil springs 33 are wound about the hinge pins 31, conveniently in the spaces between the lugs of the respective pairs 30. One end of each of these springs is fixed relatively to the fixed plate 24. The other ends 34 of the respective springs are positioned within narrow grooves 35 provided in the inner face of the fixed plate 24. These ends 34 of the springs bear against the abutting face of the movable plate 29 and serve to give it an outward movement relatively to the fixed plate, as indicated by dotted lines in Fig. 4, whenever the movable plate is released in the manner hereinafter described.

The movable plate 29 is controlled in its operation by the combination box 12, and for this purpose connections are provided between said movable plate and the combination box, which, whenever the combination box is dislocated from any cause, act to release the movable plate and permit the spring mechanism just described to throw the movable plate rapidly into an open position relatively to the fixed plate, and permit disconnection of the looped ends of the wiring.

Mounted on the outer face of the movable plate 29 is a horizontally projecting bar 36 provided with an axially extended socket 37. This socket 37 receives the horizontal pin 38, which may be fixed in the socket 37 by means of a set screw 39 screwed from one side of the bar and into the socket 37, so as to engage the pin 38. The outer end of the bar 36 is connected to a rod 40, which extends to the combination box 12. At the rear face of the combination box 12, this rod 40 is connected by a screw and nut connection 41 with the combination box. There is thus established a connection between the movable plate 29 and the combination box whereby any dislocation of the combination box, such as may be occasioned by punching or blowing, is transmitted to the movable plate 29, permitting the latter to move into open position, assisted

by the spring mechanism 33, and permit the release of the pellet 28.

When the parts are being assembled, the movable plate 29 may be rigidly held to the fixed plate 24 by a screw, indicated by dotted lines at 42, so as to avoid accidental disassembly of the wiring and the pellet 28 during the adjustment of the other parts. As soon as the mechanism has been adjusted, however, the screw 42 is removed so as to permit the control of the plate 29 by the combination box.

It will be manifest that any burning or cutting of the door and the resultant severing of either of the wire members of the wiring 15 will likewise result in the release of the relocking mechanism 14. If the wire member between the spring 19 and releasing mechanism be cut or burned through the spring of the relocking device being no longer restrained causes the relocking of the door.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a vault lock actuating mechanism, the combination with a lock, of wiring maintained normally under tension and adapted on release thereof to permit operation of said lock, said wiring including portions having looped ends, a connector engaging said looped ends for maintaining the continuity of the wiring, and means responsive to abnormal disturbance of the vault for displacing said connector.

2. In a vault lock actuating mechanism, the combination with a lock, of wiring maintained normally under tension and adapted on release thereof to permit operation of said lock, said wiring including portions having relatively disconnected looped ends, a connecting member for engaging said looped ends for maintaining the continuity of the wiring, a connecting member holding mechanism adapted normally to prevent its displacement, and means operative on abnormal disturbance of the vault for rendering inoperative said connecting member holding mechanism.

3. In a vault lock actuating mechanism, the combination with a lock, of wiring maintained normally under tension and adapted on release thereof to permit operation of said lock, said wiring including portions having looped ends, a connecting member for connecting said looped ends to maintain the continuity of the wiring, a housing surrounding said connecting member for maintaining the

latter against displacement and including a relatively movable member adapted when in open position to release said connecting member, spring mechanism for operating said relatively movable member to connecting member releasing position, a combination box, and connections between said relatively movable member and said combination box acting on dislocation of the combination box to release said spring mechanism for operation.

4. In a vault lock actuating mechanism, the combination with a lock, of wiring maintained normally under tension and adapted on release thereof to permit operation of said lock, said wiring including portions having looped ends, a pellet for engaging said looped ends for maintaining the continuity of the wiring, pellet holding mechanism adapted normally to prevent its displacement, and means operative on abnormal disturbance of the vault for rendering said pellet holding mechanism inoperative.

5. In a vault lock actuating mechanism, the combination with a lock, of wiring maintained normally under tension and adapted on release thereof to permit operation of said lock, said wiring including portions having looped ends, a connecting member engaging said looped ends for maintaining the continuity of the wiring, a housing provided with a channel receiving the looped ends of said wire and said connecting member, a movable housing member cooperating with said housing, to close said channel and prevent displacement of said connecting member, spring mechanism acting on release to operate said movable housing member to its open position, a combination box, and connections between said movable housing member and said combination box for maintaining said movable housing member normally in channel closing position relatively to said housing.

6. In a vault lock actuating mechanism, the combination with a lock, of wiring maintained normally under tension and adapted on release thereof to permit operation of said lock, said wiring including portions having looped ends, a pellet for connecting said looped ends to maintain the continuity of the wiring, a housing surrounding said pellet for maintaining the latter against displacement and including a relatively movable member adapted when in open position to release said pellet, spring mechanism for operating said relatively movable member to pellet releasing position, a combination box, and connections between said relatively movable member and said combination box acting on dislocation of the combination box to release said spring mechanism for operation.

7. In a vault lock actuating mechanism, the combination with a lock, of wiring main-

tained normally under tension and adapted on release thereof to permit operation of said lock, said wiring including portions having looped ends, a pellet engaging said looped ends for maintaining the continuity of the wiring, a housing provided with a channel receiving the looped ends of said wire and said pellet, a movable housing member cooperating with said housing to close said channel and prevent displacement of said pellet, spring mechanism acting on release to operate said movable housing member to its open position, a combination box, and connections between said movable housing member and said combination box for maintaining said movable housing member normally in channel closing position relatively to said housing.

H MILLER ANDERSON.
